UNITED STATES PATENT OFFICE.

GUSTAV RAILL-OSTERWALDER, OF REUTLINGEN, GERMANY.

FOLDING UMBRELLA.

Application filed May 9, 1925. Serial No. 29,083.

The present invention relates to an umbrella which can be closed up in length to about one-fourth of its actual dimensions. It is thus possible to pack the shortened umbrella into a case or wallet and carry it conveniently in a travelling or hand bag without being inconvenienced by the otherwise usual long stick.

The invention consists substantially in dividing both the stick and the ribs of the umbrella longitudinally and making these parts capable of being folded together by means of hinges, which can be locked by the provision of suitable means when the stick and the ribs are extended. A further improvement in the present invention is that these hinges can in each case be closed up in one direction only but are rigid on the side so that the strength of the umbrella is thereby increased.

The subject matter of the present invention is illustrated in the accompanying drawing but numerous variations may be made in the choice of the hinges and the means for stiffening them without departing from the essential feature of the present invention.

Fig. 1 shows the umbrella in a case or wallet packed for travelling.

Fig. 2 is a perspective view of the umbrella closed up.

Fig. 3 shows the umbrella stick alone closed up.

Fig. 4 is a partial longitudinal section and shows the stick extended with the hinges locked but the umbrella closed up.

Fig. 5 shows the umbrella in the position in which the closed up umbrella ribs are extended, their extended position being indicated by dot and dash lines.

Fig. 6 shows the umbrella opened and partially in section.

Fig. 7 shows a connecting joint for the umbrella stick, and

Fig. 8 shows a joint for the umbrella ribs in partial section, while

Fig. 9 is a transverse section through the joint shown in Fig. 8.

The umbrella according to the present invention has first a stick which can be closed up at two points, the separate members of

which are pivotally connected with each other. The umbrella stick consists as shown in Figs. 3 and 4 of an outer section *a* which forms the point, a middle section *b* and a handle section *c* to which the handle *d* is attached in the usual manner, e. g. by being screwed thereto. These parts of the umbrella stick are preferably solid and consist of any kind of strong light metallic alloy so as to make the umbrella light and convenient in use combined with good stability. The pivotal connection of these parts of the stick with each other is effected by joints which are movable in one direction only and which consist of a link *e* which is fastened to the parts of the stick by means of any desired kind of pivot such as rivets *f* and at the same time lies not in a slot passing completely transversely through the parts of the stick but in a groove *g* therein, so that in this way it is only possible to close the joint up towards the open side of the groove, while on the side of the stationary walls *h* it is rigid.

In the constructional form shown in Figs. 2 and 3, the handle piece *c* folds relatively to the middle section *b* in a plane at right angles to the plane of rotation of the joint between the middle section *b* and the section *a*. It is however obvious that the folding of the parts of the stick may also take place in the same plane or in any other desired manner.

In order to connect the different parts of the stick rigidly to each other when in the extended position means are provided for enabling the joints to be locked in this position. For this purpose there are provided on the solid parts *a*, *b* and *c* two tubes or sleeves *i*¹ and *i*² which surround them and which can be so pushed along on the parts of the stick that they release the joints so that these latter can be turned down or that they cover up the extended joints and surround them and so lock them. The movability of these tubes on the different parts of the stick is so limited that they cannot be moved beyond certain positions, and in particular so that the joints are just released sufficiently far or covered up so as to simplify the use of the umbrella. The

limitation of the movement of the tubes i' and i^2 may be effected by fixed stops such as rivets for example, or by stop pins k , or integral projections on the stick which slide in suitable longitudinal slots l in the tubes i' and i^2 . These longitudinal slots l may be covered over with a removable thin protecting sleeve m as shown in Fig. 4 so as to prevent the cover of the umbrella being damaged by the pins k . To enable the tubes i and i^2 to be held in their locked position, springs n , n' may be provided which can be arranged to be depressed into slots or parts of the stick as is usual in umbrellas and emerge through corresponding slots l^2 in the tubes whereby they prevent these latter from moving longitudinally. It is immaterial whether the springs emerge through the guide slots for the movement of the pins k like the springs n' in Fig. 4 or whether special slots be provided for the springs as for example for springs n and n^2 . The tubes i' and i^2 may with advantage be so arranged and be of such dimensions that when the umbrella stick is extended and locked they abut against each other and in a way form a continuous tube.

The ribs of the umbrella can be folded up longitudinally in the same way as the umbrella stick. They each consist therefore of two parts o' and o^2 , which, as shown in Figs. 8 and 9 are pivotally connected together. The joints each consist of a link member p to which the parts o' and o^2 of the ribs are pivoted by means of pins q . Owing to the link member p being U-shaped in cross section and closed underneath, the joint can again be closed on one side only namely outwards, while in the opposite direction it acts rigidly beyond the extended position. To prevent the outer rib o^2 from swinging round, the mouth r of the link is made elastic so that it will catch over the cross section of the rib parts o' and o^2 elastically and hold them securely in the extended position. The link may of course also lie inside the U-shaped rib so that its mouth catches elastically over the pivots and projecting ends of the link.

The constructional form of the umbrella is in other respects the same as in an umbrella of the ordinary kind. Struts s are pivoted on the one hand to the ribs o' and on the other hand to a sleeve adapted to slide on the stick i. e. the ordinary runner so as to enable the cover of the umbrella to be opened out as shown in Fig. 6. The ribs o' are likewise pivoted in the usual way to a crown u which however is of different construction than the type hitherto employed. It is screwed to the tube i' so that the point a of the stick can pass through it when the stick is extended. Furthermore the crown plate to which the pivots v for the ribs o' are attached is made of such

diameter that the joints w of the struts on the runner t can conveniently find room underneath it when the umbrella is closed as shown in Fig. 4.

When the umbrella is closed up as shown in Fig. 2, the tube i' is pushed on to the section a and the tube i^2 on to the middle section b , so that the joints between the parts of the stick are exposed. The ribs o^2 are turned outwards and upwards—that is to say, towards the ribs o' —while the runner t with the struts s is pushed upwards under the crown u (see Fig. 4). To open the umbrella the stick is first extended straight out and then the handle d held and the two tubes pushed together over the places where the joints are in the stick, after which the springs n , n' and n^2 are snapped into their slots, while the stop pins k strike against the ends of their guide slots l , l^2 . After the stick has been thus extended and locked the runner t is brought into its usual position over the springs n' , n^2 on the handle d and the ribs o^2 then turned down with the cover x attached to them until the links p have snapped into place. The umbrella can then be opened in the usual way.

I claim:—

1. An umbrella, embodying a stick which comprises a plurality of sections jointed together at their ends for pivotal movement into and out of mutual alinement; locking tubes slidable on said sections to cover and uncover the joints; means for limiting the movements of the tubes so disposed that in one extreme position the joints are just exposed, while in their other extreme position the tubes completely cover the joints; and catches, independent of said limiting means, for holding the tubes in the second-named extreme position.

2. An umbrella, embodying a stick which comprises a plurality of sections jointed together at their ends for pivotal movement into and out of mutual alinement; locking tubes slidable on said sections to cover and uncover the joints and provided with longitudinal slots; stop pins fixed to said sections and projecting into said slots to limit the extent of movement of the tubes, the slots having a length such that in one extreme position of the tubes the joints are just exposed, while in their other extreme position the tubes completely cover the joints; and catches, independent of said stop pins, for holding the tubes in the second-named extreme position.

3. An umbrella, embodying a stick which comprises a plurality of sections jointed together at their ends for pivotal movement into and out of mutual alinement; locking tubes slidable on said sections to cover and uncover the joints and provided with longitudinal slots; stop pins fixed to said sec-

tions and projecting into said slots to limit the extent of movement of the tubes, the slots having a length such that in one extreme position of the tubes the joints are just exposed, while in their other extreme position the tubes completely cover the joints; sleeves fitting over said slots to pro-

tect the cover of the umbrella against damage by the pins; and catches, independent of said stop pins, for holding the tubes in ¹⁰ the second-named extreme position.

In testimony whereof I affix my signature.

GUSTAV RALL-OSTERWALDER.
